(57) **CLAIM**

I claim the ornamental design for a hot lunch container, as shown and described.

DESCRIPTION

FIG. 1 is a perspective view of the container of the present invention in the closed position;

FIG. 2 is a top view of the container of FIG. 1 in the closed position;

FIG. 3 is a front elevational view of the container of FIG. 1 in the closed position;

FIG. 4 is a side elevational view of the container of FIG. 1 in the closed position;

FIG. 5 is a rear elevational view of the container of FIG. 1 in the closed position; and,

FIG. 6 is perspective view of the container of FIG. 1 in the open position.

The broken lines are for illustrative purposes only and form no part of the claimed design.
